COMBINED COMB AND THINNING RAZOR

Ng Fook Tin, 18 Hing Hon Road, 3rd Floor, Hong Kong

Filed Jan. 30, 1967, Ser. No. 5,605

Claims priority, application Great Britain Aug. 5, 1966

Term of patent 14 years

(Cl. D95—3)

Fig. 3.

Fig. 5.

Fig. 4.

FIG. 1 is an elevational view of one side of a combined comb and thinning razor showing my new design;

FIG. 2 is an elevational view of the opposite side thereof;

FIG. 3 is a cross sectional view on the line 3-3 of FIG. 1;

FIG. 4 is a cross sectional view on the line 4-4 of FIG. 1; and

FIG. 5 is a perspective view of the side shown in FIG. 1 with the parts in an open position.

I claim:

The ornamental design for a combined comb and thinning razor, substantially as shown.
